PICTURE RECEIVER

August Karolus, Leipzig, Germany, assignor to
Radio Corporation of America, a corporation of
Delaware

Application February 24, 1930, Serial No. 430,766
In Germany March 8, 1929

3 Claims. (Cl. 178—6)

The invention is concerned with the transmission of static or still pictures, or of moving pictures, and more particularly with the case where scanning or exploration and re-creation are effected not by movements of luminous points or diaphragms, but rather by the switching of cell-screens. Hence, the picture surface consists of rows of points comprising photo-electric cells (selenium, or photo-cells) for the transmitter apparatus and luminescent cells, such as glow-discharge lamps, for the receiver apparatus, while switches rotating in synchronism and under co-phasic conditions are provided so as to take care that homologous cells of the row are interconnected. Between the two change-over switches are to be inserted the amplifier and transmission means.

It is known in the prior art that change-over switches of this kind, both for entire groups of rows as well as for separate or distinct cells inside a given row of points, may consist of current-distributors driven by a motor. One or more slip brushes in rapid alternation make contact with contacts which are associated with the respective groups or with separate elements. Furthermore, inertialess switching devices are known whereby cell screens disposed in the interior of vacuum tubes in a way known from the Braun tube are to be switched over by moving pencils of electrons, these pencils of electrons being set into rotation, for example, by the action of a rotary magnetic field.

The mechanical change-over switches of the kind first named are unsuited for fine picture screens which comprise a great number of cells, on the ground that the dimensions and circumferential speeds would have to be inadmissibly high where so many contacts are needed. In the case of devices of the second kind, the main disadvantages reside in the fact that the cell screens including all of their contacts, insulated surfaces, etc. have to be accommodated in the interior of thermionic tubes, and this would be attended with considerable difficulties as regards assembling of the tubes and their treatment from a vacuum or evacuating viewpoint.

The present invention obviates the above named difficulties by providing a combination of a mechanical and an electronic change-over switch, in such manner that the former effects the circuit-changes or change-over between groups of cells (which changes proceed at a relatively low rate of speed), while the latter insures the distribution of current over the constituent elements of each cell group or bank, an opera-

tion which must proceed far faster. In this manner it is feasible to make picture surfaces of any desired size and fineness of grain, because the inertialess device and the screen need not form a unit from a constructional viewpoint. The arrangement of the vacuum tube may be simplified, although the contact frequency may be extremely high.

Fig. 1 of the drawing illustrates one embodiment which is shown by way of example, and Fig. 2 discloses a modification of Fig. 1.

The cells comprising photoelectric cells for the transmitter and glow-discharge vessels for the receiver apparatus, are arranged in vertical groups, being respectively denoted by Roman numerals I, II, III, etc., while the place or position of each individual element inside a given group is designated by Arabic numerals 1, 2, 3, etc. Only a small number of the total cells has been designated. The receiving circuit is here fed with D. C., although it could be supplied also with A. C. 20 denotes the mechanical, and 21 the electronic change-over device. The former has disposed upon its periphery r many stationary contacts 9, 9', 9'', etc. at equal intervening distances, while opposite thereto rotates a star or spider of $(r-1)$ many distributor contacts 10, 10', 10'', etc., all of the latter forming equal angles between themselves. With this arrangement which is well known in the prior art, it is possible that even $1/r$ revolution of the distributor star suffices in order that consecutively all of the r groups of cells I, II, III, etc. may be switched-in in uniform sequence. The electronic change-over switch 21 is furnished with anodes 11, 11', 11'', etc. of a number equal to r , uniformly distributed over the circumference, said anodes being coordinated to the respective places of elements 1, 2, 3, etc., as can be readily seen from the drawing. The pencil of electrons, 12, issuing from a common cathode 13 and striking the electrodes 11, 11', 11'', and whose intensity is governed by the intensity of the picture signal (for which purpose there are used controlling means well known in the prior art), is set into rotation by deflector coils 14, 15, and 16, 17 respectively, energized under dephased conditions. Its circumferential speed naturally must bear a constant relation to that of the distributor star in switch 20; to be more precise, when n_1 is the speed of rotation of the switch 20, and n_2 is that of switch 21, then the said relation is given by the expression $n_2/n_1=r^2$. In other words, the electron pencil rotates many times faster than the distributor star of switch 20.

The poles of the receiving circuit are denoted by 18 and 19. At the instant shown in the drawing, the current flows from 18 by way of distributor arm 10, contact 9, cell 5 into group IV, anode 11 and cathode 13 toward 19. In spite of the high speed of switching, all of the contacts are accurately established by virtue of the absence of inertia and the accuracy of control of the electron pencil. Indeed, the switching-in and 10 switching-out are accurately defined, and there arise no difficulties of insulation.

The mechanical change-over switch 20 need not be designed in a way as here shown. Indeed, its place may be taken by an ordinary distributor 15 comprising a single circulating or rotating contact member, though in this instance the speed of rotation must be r times higher.

As regards the construction of the electronic change-over device or switch 21 reference must 20 be made here to the disclosure, instructions and examples given in the prior art. One particular advantage of the arrangement as here shown resides in that, in the presence of r^2 picture points, the cathode-ray tube (electronic tube) 21 needs 25 to have only r lead-ins brought to the electrodes 11, 11', 11'', etc., contradistinct from what is true of earlier suggestions where all of the cells are switched in and out by purely electronic means and where r^2 lead-ins are furnished in 30 order to establish connection with the cell screens located outside the tube. This simplification, as will be noted, is insured in the present invention by combining the mechanical group or bank switch with an electronic change-over 35 device for the individual cells.

Since it would hardly be possible to convey a maximum current for energizing the luminous cells by way of the electron pencil of the switch tube 21, a mediate acting electronic distributor 40 arrangement may be used in which the cathode-ray-pencil subject to intensity control by the receiver, does not carry the operating current of the cell screen, but serves merely as a path of least resistance for releasing the working current. For this purpose could be employed, for 45 example, the instantaneously varying charges set up by the rotating electron pencil at distinct control electrodes. For instance, the rotating cathode-ray-pencil controlled in its intensity by 50 the incoming current may be used to more or less charge up negatively grid electrodes of amplifier systems. The anode current which will be caused to thus decrease more or less diminishes the potential difference across the ends of a resistance inserted in its circuit. This potential 55 difference acts in the form of a counter E. M. F. in the circuit of the luminous cell and its source. Since the counter E. M. F. diminishes as the control electrodes are charged up negatively, a correspondingly reinforced current impulse 60 associated with greater brightness is made to flow across the luminous cell. The grid electrode, of course, together with the cathode coordinated to it must be united by a high resistance in order 65 that unduly fast leaking away of the negative charge must be precluded.

A somewhat different circuit arrangement is shown in Fig. 2 in which of the groups of luminous cells only banks I, II and III are illustrated, while 70 inside these only cells 1 and 2 are indicated. The group supply leads are united with the contacts 9, 9', 9'', etc. of the mechanical change-over switch 10 by which the current is able to flow from the positive pole of the source 18 through the 75 particular luminous cell which happens to be in

circuit. The rotating electron pencil 12 impinges upon the distributor electrodes 11, 11', 11'' confined inside the vacuum vessel, from which leads are brought to the control grids 36, 37, which are associated with the coordinated cathodes 38, 39, by way of high resistance 40, 41.

These amplifier systems should most suitably be provided with a high reciprocal amplification factor so that, in the state of rest or when unenergized, a comparatively strong current will flow by way of the anodes 32, 33 through the resistances 34, 35. The plate current source for supplying plate current through anodes 32, 33, shown, is denoted by 31, while 30 designates the joint heating battery for all of the amplifier cathodes 38, 39, etc. At suitable points on the anode resistances 34, 35, a biasing potential is taken off for the control grids 24, 25, which govern the flow of the current of the luminous cells. For this purpose the anodes 22, 23, and the hot cathodes 26, 27 are provided. The electrodes 24, 25, etc. are united by way of high grid resistances 28, 29, with the cathodes 26, 27. Reciprocal amplification and biasing potential are so chosen that the flow of current in these systems (22-26, and 23-27 respectively) is shut off in unenergized condition. Now, as soon as a more or less strong electronic current 12, as shown, happens to impinge upon the distributor electrode 11' whenever the picture element in the transmitter is more or less bright, then the grid electrode 36 becomes charged negatively to a marked degree, the anode current in the resistance 34 decreases, and the potential at the point where the potential for grid electrode 24 is derived becomes more markedly 105 positive, with the result that the circuit 22-26 becomes more or less permeable. As a consequence, a "brightening" current of regulated intensity will be caused to flow from the positive pole 18 by way of the distributor arm 10, contact 9'', glow-discharge cell 1 in group III, plate 22 and filament 26 to the return conductor 19 united with the negative battery pole. The different inter-electrode gaps will thus be opened up as the cathode-ray pencil 12 travels over the distributor electrodes in a way free from sluggishness, so that the flashing up of the various cells along a bank can be accomplished at a high rate of speed.

The accompanying drawing and specification 115 show by way of example one of the several forms which the invention may assume, but I believe myself to be entitled to make and use any and all modifications such as would readily suggest themselves to those skilled in the art, and such as 120 would fall fairly within the spirit and scope of the invention as set forth in the appended claims.

Having now described my invention, what I 125 claim and desire to secure by Letters Patent is the following:

1. In a television system, a plurality of image producing points, a plurality of independently energizable sets of conductors arranged in intersecting patterns and having one of said image producing points connected at each intersection, a thermionic device connected with each conductor of one of said sets, means for normally preventing current flow through said thermionic devices in the absence of impressed signals thereon, an inertialess controlling element for energizing sequentially thermionic device to produce trigger action in accordance with received signals so as to supply controlled currents to each of the conductors of one of said sets in sequence, and mechanical means for limiting the effect of said 130

- supplied energy to a single point of each of said conductors.
2. In a television system, a plurality of image producing points, a plurality of independently energizable sets of conductors arranged in intersecting patterns having one of said image points connected at each intersection, a thermionic relay device connected with each conductor of one of said sets, a second thermionic relay device connected with each of said first-named thermionic devices, means for normally maintaining each of said second-named thermionic devices in an operative state, means normally responsive to a current flow through each of said operative thermionic devices for biasing each of said first-named thermionic devices to cut-off, a cathode ray instrumentality for influencing each of said second-named thermionic relay devices sequentially for biasing said amplifiers in sequence to substantially a cut-off point for increasing the flow of current through each of said first-named thermionic relay devices so as to sequentially pass current through each conductor of one of said sets, and a mechanical means for selecting the point at which the current passing through each conductor of said last-named set is effective.
3. In an electro-optical image producing system, a plurality of light producing elements arranged at the intersection of a plurality of conductors arranged in the form of abscissi and ordinates whose concurrently energized intersections determine the instantaneous light values produced from said elements, means for sequentially energizing the abscissa conductors at predetermined rate, a first thermionic relay connected with each ordinate conductor, a second series of normally operative thermionic relays having the output circuit connected with the input circuit of each first thermionic relay to bias each first thermionic relay normally to cut-off during periods of operation of each second relay, and an electronic means for sequentially triggering the relay of the second series so as to reduce the space current through the relays of the second series and thereby render the relays of the first series operative in sequence to pass current through the ordinate conductors.

AUGUST KAROLUS.
